CONSOLE

Ward J. O'Connor, Bayonne, N. J., assignor to
The Lummus Company, New York, N. Y., a corporation of Delaware

Application October 7, 1949, Serial No. 5,341

Term of patent 7 years

(Cl. D26—5)

To all whom it may concern:

Be it known that I, Ward J. O'Connor, a citizen of the United States, residing at Bayonne, county of Hudson, State of New Jersey, have invented a new, original, and ornamental Design for a Console, of which the following is a specification, reference being had to the accompanying drawing, forming a part thereof.

Fig. 1 is a perspective view of a console, showing my new design; and

Fig. 2 is a top plan view thereof, upon a reduced scale.

The rear and the sides of the article are plain.

I claim:

The ornamental design for a console, as shown and described.

WARD J. O'CONNOR.
